UNITED STATES PATENT OFFICE.

CHARLES PELISSIER, OF CONCORD, NEW HAMPSHIRE.

MACHINE FOR FORMING HARNESS-LOOPS.

SPECIFICATION forming part of Letters Patent No. 366,024, dated July 5, 1887.

Application filed April 20, 1887. Serial No. 235,448. (No model.)

To all whom it may concern:

Be it known that I, CHARLES PELISSIER, a citizen of the United States, residing at Concord, in the county of Merrimac and State of New Hampshire, have invented certain new and useful Improvements in Machines for Forming and Stamping Loops, of which the following is a specification.

The object of my invention is to improve the present machinery by which harness-loops are made; and it consists of the combination of devices for taking up the loose leather, forming and embossing the loop free from wrinkles, all of which will be described below, 15 and pointed out in the claims.

In the accompanying drawings, forming part of this specification, similar letters indicate corresponding parts throughout the various views, of which—

20 Figure 1 is a front elevation of my improved machine. Fig. 2 is a sectional plan of same. Fig. 3 is an enlarged sectional elevation of the dies and some of their operative parts, and Fig. 4 is an enlarged view of a sliding wedge, 25 by which the die which bears upon the top of a loop is moved upward.

A is the machine-bed, and B B are blocks, within which are rigidly secured suitable nuts, C C, to which are threaded the horizontal 30 screw-shafts D D. Columns E E rise from the blocks B B at either end of said bed and support a cap-piece, F, all being held in place upon said bed A by means of bolts G and nuts g. A vertical screw-shaft, H, passes through 35 the cap-piece F at I, and carries at its upper end a lever, J. A follower, K, is swiveled to the lower end of said screw-shaft H, and is guided in its vertical movement by tongues e, formed upon the columns E, and by guide-

40 rods L, carried upon the follower and passing upward into the cap-piece F. The screws D D, which are provided, one with a right and the other with a left thread, have a smooth portion, to which are splined the spur-gears M M. These are prevented movement end- 45 wise by reason of the bearings N N, supporting said screw-shafts D D, and the stands O O, which are bolted to the bed A. Thus the said screw-shafts are permitted the necessary end 50 movement within the gears M M and the bearings N N while being rotated by the said gears

M M and the pinions P P, which mesh with each other. The pinions P P are carried upon a shaft, Q, supported in bearings R R, upon one end of which belt-pulleys may be applied, 55 or a crank may be substituted, if desired, and the said movement be accomplished by hand. The screw-shafts D D act against or they may be swiveled in suitable blocks, S S, which present a flat surface to the side die-plates, T, (see Fig. 3,) and are provided at either side, 60 near their farther end, with a boss, s, to which is bolted a lever-spring, s'. These springs bear with great force upon end blocks, U U, and by reason of their chamfered sides the 65 pressure of said springs increases with the inward movement of the said screws D D.

V is the bed-die, which is loosely tenoned at either end into the end blocks, U U. (Seen in Fig. 1.)

70 The surfaces of the dies T V which come in contact with a loop may be engraved for ornamentation, as desired.

Pressure-blocks of the desired width and length may be placed at the under side of the 75 follower K, and secured thereto by reason of the ears k and screws k'.

W is a sliding wedge, which is adapted to move transversely upon the bed A, or within a groove, a, formed for the purpose. This is 80 provided with a threaded portion, w, to which is threaded the screw-shaft w', carried in a bearing, W', and having upon its outer end a spur-gear, X, meshing with the spur-gear X', mounted at one end of a shaft, Y, and by means 85 of the crank y at the opposite end motion is communicated to the said wedge W. The bed-die V is supported by this wedge W, the object being to render said die easily adjustable and independent of the others.

90 The operation of the machine when forming a loop is as follows, to wit: A loop is placed a between the dies T T, strap side or bottom side up. Then the said dies are moved onto the loop by aid of the blocks S S and the screws D D with considerable pressure. The said dies T T are adjustably supported by means of the 95 springs S', which are conveniently connected to the blocks S at s', and whose outer ends enter the sockets t, formed in the dies T. These 100 may be set as desired by aid of the set-screws t', threaded to ears projecting from the blocks

S for this purpose. The next movement is preferably to put pressure onto the loop from below by causing the wedge W to advance under the die V sufficient to straighten out the 5 loose leather, when, after applying pressure from above by the screw H, the final pressure may be given to the die V, as before.

Having described my invention, what I claim, and desire to secure by Letters Patent, is—

- 10 1. In a press for forming harness-loops, the combination of the dies T V, their operating mechanism, the end blocks, U, and mechanism, substantially as shown, whereby the die V may be raised as desired, for the purpose 15 set forth.
2. In a press for forming harness-loops, the combination, with the die V, of the adjustable suspended dies T and their operating mechanism, substantially as and for the purpose 20 explained.
3. The combination of a longitudinally-bevelled slide, the machine-bed provided with a transverse groove, into which said slide is fit-

ted, the die V, the adjustable suspended dies T, and mechanism, substantially as described, 25 for moving said slide across said bed, for the purpose explained.

4. The combination, with the dies T, having sockets t, and blocks S, having ears to which are threaded screws t', of springs S', constructed and operating substantially for the purpose set forth.

5. The combination of the bed-die, the adjustable suspended dies, a longitudinally-bevelled slide, the machine-bed having a transverse groove, into which said slide is fitted, a screw-shaft threaded to a portion of said slide, and operating mechanism whereby said screw-shaft is rotated, substantially as and for the purpose set forth.

In testimony whereof I affix my signature in presence of two witnesses.

CHARLES PELISSIER.
